METHOD OF MAKING BUFFING WHEELS

George Albert Lyon, Detroit, Mich.

Application September 16, 1950, Serial No. 185,304

2 Claims. (Cl. 51—193)

1

This invention relates to a method of making an abrading wheel and more particularly to a buffing wheel of the type having lapped layers of cloth.

An object of this invention is to provide a method of making an improved and simplified form of buffing wheel whereby the wheel can be economically manufactured from a continuous strip of buffing material as distinguished from annular discs of buffing material now commonly used in commercial forms of buffing wheels.

Another object of the invention is to provide a method of winding strip buff material in a spiral groove on a wheel by a cable in such a way that the material is bulged and pinched around the cable as the cable and buff material is tightly drawn into the groove of the wheel.

In accordance with the general features of this invention there is provided in a method of making a buffing wheel out of a strip of lapped material folded about a cable for securing the strip in a peripheral spiral groove of a wheel, the steps of stitching layers of buffing material along two substantially parallel spaced lines at a generally medial area in a continuous strip of the material, the stitching being generally parallel to the edges of the strip, applying a winding cable to the strip between said lines of stitching, winding the strip and cable into the spiral wheel groove, and contemporaneously folding the sides of the strip about the cable in the groove while crowding and bulging excess material at the fold, over the cable so that the cable is substantially enveloped by the folded material.

Another feature of the invention relates in using the cable and the bulged material between the legs of the folded strip extending radially from the cable to form an air space between the folded legs for assisting in the cooling of the buffing material.

Other objects and features of this invention will more fully appear from the following detailed description taken in connection with the accompanying drawing which illustrates a single embodiment thereof and in which:

Figure 1 is a fragmentary plan view of a strip of lapped buffing material with parallel lines of stitching at its medial area and showing a cable located between the parallel lines;

Figure 2 is a fragmentary cross-sectional view lengthwise of the strip shown in Figure 1 and showing the lapping or tucked folds of the strip;

Figure 3 is a fragmentary cross-sectional view through a portion of a spiral groove in a wheel and showing the cable in the process of folding

2

and pulling the strip of Figure 1 into the groove; and

Figure 4 is a fragmentary cross-sectional view similar to Figure 3 showing the cable and strip tightly engaged in the wheel groove and showing the excess material pinched or bulged together over the cable between the legs of the folded strip.

As shown on the drawing:

10 It is believed that my novel method may be fully understood from a description of the subject matter illustrated in the accompanying drawing. Also, it should be noted that I have not shown in detail the construction of the buffing wheel with a spiral groove in it since any suitable wheel can be employed having such a groove in its periphery, although my invention is particularly useful in conjunction with a wheel such as that shown in my copending application 20 Serial No. 135,675, filed December 29, 1949.

The reference character 10 designates generally a continuous strip of buff material such as is commonly used in buffing and polishing wheels at the present time. For illustration, this strip 25 can be made of a cotton drill material cut on the bias, as is conventional practice in the buff art.

The strip is made up of a multiplicity of layers such, for illustration, as three or four formed into a plurality of laps or tucks 11 (Figure 2). Any conventional tucking machine may be used 30 for this purpose.

In accordance with the features of this invention I have first stitched the strip lengthwise and across the laps or folds to provide two parallel lines of stitching 12—12 (Figure 1) located 35 generally at the medial or middle area of the strip. Any suitable sewing machine may be used for the purpose of applying these parallel lines of stitching to the strip 10.

40 Then, in accordance with the next step of my method, I align the strip with the cable 13 so that the cable will be parallel to or between the two lines of stitching 12—12. The cable 13 is preferably a twisted wire strand cable and is adapted to have one end anchored by any suitable

45 means to a wheel 15 provided on its outer periphery with a spiral groove 16. In other words, the cable is anchored to the wheel in a position to enter the groove 16, as shown in my co-pending 50 patent application. The periphery of this wheel can be given any desired contour consistent with the peripheral shape of the ultimate buffing surface desired.

Then the cable is progressively wound in the 55 groove 16 along with the strip 10. In the course

of this winding, as shown in Figure 3, the medial portion of the strip between the lines of stitching 12-12 is folded and forced into the groove 16 by the cable and the side legs 20 of the folded strip are brought toward each other until the folded portion 18 of the strip is completely in the groove, as shown in Figure 4.

Now, in the course of this folding or bending of the strip at its medial portion, the side of the strip facing the cable is bent on a shorter radius than that of the outermost surface of the folded portion 18, and as a consequence, excess material is squeezed or bulged at 19-19 from the legs of the fold over the cable.

By the time the cable and the folded strip are completely in the groove, the bulged portions 19-19 immediately inside the stitching 12-12 will have been pinched together over the top of the cable so that the cable is substantially enveloped all around its cylindrical surface by the material of the strip. I find that this is very advantageous in that the material locks itself to the cable without the necessity of having any stitching at the locale of the bulged portions 19-19. In other words, it was first thought that the strip would have to be folded around the cable and stitched thereto at the areas 19-19, but I find that these operations can be eliminated. This means that the winding of the cable itself serves as the means for folding the strip and also of firmly securing the folded strip in position with the side legs 20-20 of the strip projecting generally radially from the wheel (Figure 4).

It will be appreciated that the extremities 21-21 of the strip legs 20-20 constitute the buffing surface of the wheel and since the strip is tightly anchored in the spiral groove 16, such surface follows the peripheral contour of the wheel.

In addition, I find that the bulged portions 19-19 tend to separate the legs 20-20 at their junction with the cable so that an air space is provided at 22 between the legs through which air

can circulate for cooling purposes in the use of the buffing wheel.

It will be understood that modifications and variations may be effected without departing from the scope of the novel concepts of the present invention.

I claim as my invention:

1. In a method of making a buffing wheel out of a strip of buffing material folded about a cable for securing the strip in a peripheral spiral groove of a wheel, the steps of stitching layers of buffing material along two substantially parallel lines at a general medial area in a continuous strip of the material, applying a winding cable to the strip between said lines of stitching, winding said strip and cable into the spiral wheel groove and contemporaneously folding the sides of the strip about the cable in the groove while crowding and bulging the excess material, due to the folding of the strip, over the cable so that the cable is substantially enveloped by the folded material in the groove.

2. In a method of making a buffing wheel out of a strip of buffing material folded about a cable for securing the strip in a peripheral spiral groove of a wheel, the steps of stitching lapped layers of buffing material along two substantially parallel lines at a general medial area in a continuous strip of the material, applying a winding cable to the strip between said lines of stitching, winding said strip and cable into the spiral wheel groove and contemporaneously folding the sides of the strip about the cable in the groove while crowding and bulging the excess material, due to the folding of the strip, over the cable so that the cable is substantially enveloped by the folded material in the groove, the excess material being pinched together from both sides of the fold over the cable and spacing the folded legs to define an air passage between the legs for assisting in cooling the buffing material in use.

GEORGE ALBERT LYON.
